UNITED STATES PATENT OFFICE.

JOSEPH P. HALLENBECK, OF NEW YORK, ASSIGNOR TO THE NATIONAL MACHINE COMPANY, OF TROY, NEW YORK.

MACHINE FOR SEWING ON BUTTONS.

SPECIFICATION forming part of Letters Patent No. 425,422, dated April 15, 1890.

Application filed August 24, 1889. Serial No. 321,862. (Model.)

To all whom it may concern:

Be it known that I, JOSEPH P. HALLENBECK, a citizen of the United States, residing in the city of New York, in the State of New York, have invented certain new and useful Improvements in Button-Sewing Machines, of which the following is a specification, reference being had to the accompanying drawings, in which similar parts are marked by like letters in the different views, and the directions in which some of the parts move are indicated by adjacent arrows.

This invention relates to machines for sewing to clothing and other articles or fabrics buttons having perforations or eyes through them from side to side; but some parts of the invention are applicable to machines for sewing on buttons having shank-eyes.

The general objects of this invention are to furnish a sewing-machine with excellent mechanism for holding and intermittently moving a button having four eyes and presenting the eyes in succession to the needle to sew on the button by stitches from eye to eye progressively around the circuit of the eyes, to provide such mechanism with adjusting devices whereby buttons having eyes at widely different distances apart can be thus sewed on, to provide such mechanism with adjusting devices whereby buttons having four eyes or two eyes can be sewed on by stitches extending to and fro between two opposite eyes and across the center of the button, to produce a button holder and carrier having superior means for receiving and holding such buttons and applying them to the fabric in the sewing-machine, to furnish the button holder and carrier with adjustable devices for holding and carrying buttons of very different sizes, to provide the button-carrying mechanism with excellent means for automatically securing the sewing on of a button by a certain predetermined number of stitches, to provide such means with adjusting devices whereby the sewing on of buttons by certain different numbers of stitches can be secured, to provide means for automatically stopping the sewing-machine when the button-carrier shall have moved a certain predetermined number of steps, and to provide a device whereby the machine can be con-

veniently started and kept in motion. Other objects of the invention are hereinafter set forth. These objects are attained by the mechanism illustrated in the accompanying drawings, in which—

Figure 1 represents in side elevation and partly in section a button-sewing machine embodying one form of this invention, the section being mainly at about the line $z z'$ in Fig. 2, which is a plan of the under side of the same machine. Fig. 3 shows a section of a portion of the bed-plate of the same machine at the said line $z z'$ and an elevation of some parts of the mechanism, as seen in the direction of the arrow y in Fig. 2. Fig. 4 represents a section of the lower portion of the same machine at the line $x x'$ in Fig. 2 and an elevation of some parts as viewed in the direction pointed by the arrow w , and Fig. 4^a is a plan and partial section of parts at the line $w^2 w^2$ in Fig. 4. Fig. 5 shows a section of the lower portion of the same machine at the line $v v'$ in Fig. 2 and an elevation of some parts as seen in the direction of the arrow u , and Fig. 5^a is a plan and partial section of parts at the line $w^3 w^3$ in Fig. 5. Figs. 6, 7, and 8 represent some detached parts of the mechanism shown in Fig. 2. Fig. 9 shows in plan and on a larger scale the button holding and carrying mechanism represented in elevation in Fig. 1, and Fig. 10 shows the same mechanism in partial section at the line $t t'$ in Fig. 9. Fig. 11 is a plan of the under side of a part of the button-holder shown in Figs. 9 and 10; and Figs. 12, 12^a, and 13 are isometrical representations of some detached parts of the same button-holder. Figs. 14, 15, 16, 17, 18, 19, 20, 21, and 22 are isometrical illustrations of detached parts of the same button holding and carrying mechanism shown in Figs. 9 and 10.

This invention is mainly applicable to various kinds of well-known sewing-machines. The drawings illustrate it applied to a sewing-machine manufactured by the Singer Manufacturing Company. Of that machine, A represents the bed-plate; A', the overhanging arm; B, the revoluble driving-shaft; B', the needle-bar, which is depressed and elevated at each revolution of said driving-shaft; C, the shaft which carries the hooked shuttle

and is oscillated at each revolution of the driving-shaft by the intervening crank B^3 , connecting-rod B^3 , rock-shaft C' , having the arms $C^2 C^3$, and the arm C^4 on the shaft C and 5 engaging the arm C^3 ; and O is the feed-actuating rock-shaft having an arm O' , connected with the driving-shaft by the rod B^4 and eccentric B^5 .

As a means for carrying a button-holder 10 holding a button, as Y , Figs. 9 and 10, having four eyes 1 2 3 4, in a circuit, so as to present each of the eyes in succession to the needle a of the sewing-machine, the button-holder is secured to a primary slide D , having a socket 15 b , Fig. 16, with a crank-pin or eccentric E , fitting in said socket and secured to a revolvable shaft or carrier F , mounted to rotate in a fixed position or socket b' , Fig. 10, and connected to the driving mechanism of the sewing-machine by devices which cause the rotation of said crank-pin or eccentric by steps of equal length and equal in number to the 20 number of eyes in the button. The slide D is also provided or furnished with a secondary slide G , having a guideway, as $c c$, for said primary slide and furnished with means for insuring the movement of said secondary slide bodily and equally in all its parts to and fro laterally to said primary slide and said guideway, so that the intermittent rotation of said 25 crank-pin or eccentric E causes the positive step-by-step movement of every part of said primary slide and attached button-holder in a true circle equal in diameter to the diameter 30 of the circle described by the center of said crank-pin or eccentric. In carrying out this part of my invention any suitable known means may be used to secure the movement of said secondary slide bodily to and fro laterally to said primary slide in a course perpendicular or somewhat inclined to said primary slide or in an arc of a circle or a curved course.

As a superior means for accurately guiding 40 the secondary slide G and the primary slide D , with its attached button-holder, when actuated by the eccentric E , fitting in the socket b in the primary slide, I provide a stationary base-plate H , Figs. 9, 10, and 14, which supports the two slides and has a guideway $d d$, Fig. 14, in which fit and slide wings $e e$, Fig. 15, on the slide G , which has guides $c c$, in which the primary slide D fits and is moved to and fro by the eccentric E , having its carrier F mounted to rotate in and on said base-plate.

To provide means for properly presenting 50 to the needle of the sewing-machine buttons having their eyes in circles of different diameters or at various distances apart, I combine with the primary slide and its attached button-holder a laterally-movable guideway for the primary slide, means to direct the lateral movements of said guideway, an eccentric fitting in a socket in the primary slide, a revolvable support which carries the eccentric and revolves it step by step, and means by which

the eccentric can be secured to its said support at different distances from its axis of revolution.

To provide means for securing the eccentric upon its carrier at different distances from its axis of revolution, I form the eccentric E , Figs. 10, 18, and 19, and its carrier F , Figs. 10, 14, and 17, one with a radial groove f and the other 70 with a corresponding tongue f' , adapted to fit and slide in said groove, and have through the eccentric a suitable perforation f^2 and a clamping-bolt I , extending through the perforation f^2 and engaging with the carrier F , 80 whereby the eccentric can be secured to the carrier at whatever position it shall be set thereon.

To facilitate the adjustment of the eccentric E on its carrier F , there is introduced 85 upon the eccentric a cap-piece I' , Figs. 9, 10, and 20, having a central perforation g , through which the clamping-bolt I extends, and a cam-slot h , into which extends a pin i , Figs. 10 and 19, fast on the eccentric, so that upon loosening the clamping-bolt and turning the cap-piece I' to or fro upon the eccentric and about the bolt I as a pivot the eccentric will be slid radially along the ways $f f'$ by the cam-slot h and pin i in or out upon the carrier F to different 90 distances from its axis of rotation, and can be there clamped fast with the cap-piece I' by tightening said clamping-bolt.

To further facilitate the adjustment of the eccentric upon its carrier, I form in the periphery of the carrier F a recess j , Figs. 14 and 17, and also form in the stationary support H of the carrier a slot j' , so arranged that when the carrier is turned into a certain position its recess j will register with or be as an 105 extension of the slot j' , as shown in Fig. 14. I also have a stop-bolt J , Fig. 22, which can then be inserted through the slot j' into the recess j , so as to prevent the turning of the carrier F while the eccentric E is being readjusted and clamped fast thereon, as above 110 described, and so that the bolt J can be withdrawn from the recess j to let the carrier revolve.

As regards the above-described parts of my 115 invention, the button-holder attached to the slide D may be of any suitable known kind.

To provide a button-sewing machine with improved means for conveniently receiving, centering, and securely holding and carrying 120 buttons having eyes through them, I have a fabric-presser K , Figs. 9 and 10, so secured to a suitable carrier, as D , that said fabric-presser can be freely elevated and depressed and retained upon the fabric, and have the 125 foot of said presser formed with a recess e' and provided at the sides and end of that recess with lateral guide-bearings k , Fig. 9, so as to just permit a button to be inserted edge-wise between them and thereby centered, said 130 lateral bearings being furnished with thin lips l , projecting inward at the lower edges of the bearings. I also have a somewhat elastic button-presser L , attached at one end to the

shank of the fabric-presser K and having its foot formed with a recess e^2 , and shaped and arranged so as to permit the button to be easily pressed in between it and the lips l and the edge-bearings k , and so as to then press down upon the inserted button outside of the circuit of its eyes, and thereby securely hold the button when such button-holder is elevated to permit the insertion and removal of buttons and when depressed upon the fabric X', as in Fig. 10, while sewing on a button.

Any suitable known means can be used to secure the button-holder to its carrier and to elevate and depress the same—as, for instance, such as is shown in Figs. 1, 9, and 10, wherein a part K', to which the part K is firmly attached, is hinged at d^1 to a standard d^2 on a part D', which is firmly attached to the carrier D, and has a vertically-adjustable screw-post d^3 extending upward loosely through an aperture in the part K' and surrounded by a spring d^4 , compressed between the parts D' and K', and a cam-lever d^5 is mounted on the post d^3 , over the part K', which is pressed upward against the cam-lever by the spring d^4 . When the cam-lever d^5 is turned into its position in Figs. 9 and 10, it presses the button-holder down upon the fabric X', and thereby clamps the fabric upon the thin plate D', which is attached to the part D' and extends over and slides upon the cloth-plate a', Fig. 10, and has an aperture d^6 , Fig. 21, about the needle-hole a^2 and of greater size than the circle of the eyes of the buttons to be sewed on. When the cam-lever d^5 is turned into another position, the spring d^4 elevates the button-holder in the course of the broken line t^2 in Fig. 10 to permit the free removal from the button-holder of a button sewed to a fabric and the easy insertion of another button into the button-holder.

I generally make the button-presser L sufficiently elastic to permit buttons of the same or slightly-different thickness to be readily inserted and securely held by and between it and the lips l and bearings k of the fabric-presser.

To adapt this button-holder to receive and hold buttons of greatly-different thickness, I attach the button-presser L to the fabric-presser K by a suitable adjusting-clamp—as, for example, by having the seat portion l^2 of the part L rest on the ends of four screws c' , which fit in and are adjustable through screw-sockets c^2 , Fig. 12, through the part K—and a clamp-screw c^3 , having its head bearing on the part L and its shank extending through a perforation c^4 , Fig. 13, in that part, and screwing into a screw-socket c^5 in the part K.

When the button-holder is to be used to hold buttons of equal diameters, the bearings k for the edge of the button and the lips l for supporting the under side of its rim may all be on one integral stock.

To make the button-holder capable of receiving and holding buttons of very different

diameters, I provide three sub-feet m , Fig. 12^a, each with a lateral bearing k and lip l , and with a tongue n , having therein a screw-socket n' and extending upward and fitting into one of three longer slots n^2 , Fig. 12, arranged as at three sides of a square through the plate of the fabric-presser K, and each furnished with a clamp-screw n^3 , fitting in the screw-socket n' , and the under side of the head of the screw bearing upon said slotted plate, substantially as indicated by Figs. 9 and 10, so that thereby the three sub-feet m can be readily adjusted and firmly secured to said plate with their guide-bearings k at various distances from a common center. The lips l may be rigid on the sub-feet m , or may consist of the free projecting ends of thin sheet springs extending under and along the sub-feet and united to the heels thereof, as indicated by the lines at m' in Figs. 10 and 12^a.

By the above-described adjustability of the button-holder it is adapted to receive and hold buttons of equal diameters and different thicknesses, and buttons of equal thicknesses and different diameters, and buttons of different diameters and different thicknesses.

As regards the above-described parts of my invention, any suitable-known means can be used to revolve the carrier F of the eccentric E step by step in concord with the movements of the needle-carrier of the sewing-machine. As an improved means for that purpose, I have fast on the carrier F a bevel-gear F', Figs. 1, 1, and 2, engaging with a bevel-gear M, mounted to freely rotate upon the oscillating shaft C, supported by fixed bearings y', and I have fast on the gear M a ratchet M', Figs. 2, 4, and 8, furnished with a driving-pawl N and pawl-carrier N', mounted to vibrate on shaft C, and having an arm N², jointed to a rod N³, which is jointed to an arm O², fast on the rock-shaft O, which is mounted on the bearings x² and has an arm O', connected to the driving-shaft B by the eccentric B⁵ and connecting-rod B⁴, whereby the carrier F and eccentric E will be turned a step at each revolution of said driving-shaft.

To render the mechanism capable of sewing on buttons having four eyes by stitches from eye to eye in succession around the circuit of the eyes, and also capable of sewing on buttons by stitches extending across the center of the button between two opposite eyes, the gear M may have teeth of a number multiple of the number of teeth in the gear F', and the number of teeth in the ratchet M' may be equal to or a multiple of the product of the number four and the ratio of the numbers of teeth in the two gears—as, for example, when the number of teeth in the gear M is eighteen and in the gear F' is nine the ratio is two, which multiplied by four gives the product eight as a proper number of teeth for said ratchet; also, the rod N³ may be jointed to the arm O² of the rock-shaft O by a pivot-coupling, as P, Fig. 4^a, which is adjustable along that arm, as indicated in Fig. 4, from the

point o to the point o' . With this construction when the rod N^3 is jointed at o to the arm O^2 , as shown by full lines in Fig. 4, the pawl N will be moved by the arm so as to 5 turn the ratchet M' a step equal to only one of its eight teeth, and thereby turn the gear F' , shaft F , and eccentric E through only one-fourth of a revolution, as required in sewing on four-eyed buttons from eye to eye in a 10 circuit. When the rod N^3 is jointed by the pivot-coupling P , or its equivalent, to the arm O^2 at o' , Fig. 4, the pawl N will be moved by each rocking movement of said arm so far as to 15 turn the ratchet M' a step equal to two of its eight teeth, and thereby turn the gear M through one-fourth of a revolution and the gear F' , carrier F , and eccentric E one-half of a revolution, as when stitching across the center of a button through and between its 20 opposite eyes.

M^2 is a collar fastened adjustably to the shaft c to retain the gear M in proper engagement with the gear F' and to keep the driving pawl N and its carrier N' in proper relation to the ratchet M' , and M^3 is an adjustable friction-brake bearing against the sleeve of said ratchet to secure its accurate movement by said driving-pawl and to prevent the movement of the ratchet by the shaft which 25 supports it.

Q is a friction-disk fast on the driving-shaft B , and Q' is a corresponding friction-disk, grooved to receive a driving belt or band and loose upon and slightly movable along that 30 shaft. R is a shipper mounted on a stationary pivot at p and arranged so that upon moving it in the direction of the arrows w' in Fig. 1 the disk Q' while revolving will be pressed by the shipper against the disk Q to rotate it, 35 and thereby the shaft B , and so that upon moving the shipper in the opposite direction it will release the disk Q' from the disk Q to let it and the shaft B stop.

R' is a brake united to the shipper R and 40 arranged so that when the shipper releases the disk Q' from the disk Q the brake will then bear against a projecting part p' of the disk Q , as shown in Fig. 1, to stop the machine, and so that when the shipper presses 45 the disk Q' against the disk Q the brake R' will be removed a little from the projecting part p' of the latter disk, as in Fig. 2.

S is a rod jointed at p^2 to the shipper R and 50 mounted to slide to and fro lengthwise in bearings through stationary brackets or lugs $u' u^2$. The rod S has a collar S' fastened thereon, and is furnished with a spring S^2 , which is compressed between the collar S' and lug u^2 , so as to constantly tend to move 55 the rod S in the direction of the arrow v^2 , and thereby move the shipper R , so as to release the disk Q from the disk Q' and apply the brake R' to the former disk. Another collar S^3 is fast on the rod S and has lugs q , between 60 which is a pin q' on the short arm of a lever T , which is pivoted at q^2 to a bracket q^3 on the bed-plate A , so that by pressing down the 65

long arm of that lever from its position in Fig. 1 to its position in Fig. 3 the rod S will be moved in the direction of the arrow v^3 , 70 Fig. 1, in opposition to the pressure of the spring S^2 , and will move the shipper so as to press the disk Q' against the disk Q and remove the brake R from the latter disk, and thereby start the machine and keep it in 75 motion.

To avoid all necessity for continuously pressing down the long arm of the lever T while the machine is in operation, and to provide means for automatically stopping the 80 machine when it has made a certain predetermined number of stitches in sewing on a button, I provide a revoluble thrust-bearing U , Figs. 1, 2, 3, 6, and 7, for the slide-rod S and the follower U' on said rod, and have on 85 said revoluble bearing a ratchet U^2 , Fig. 5, furnished with a driving-pawl V and its carrier V' , pivoted at r to a connecting-rod W , which is jointed to an arm O^3 on the rock-shaft O , from which the button-feeding mechanism is actuated, so that for each step movement of the button-carrier the thrust-bearing U will be turned a step. I also have the parts U U' formed with abrupt ledges s s' and with contiguous bearing-surfaces s^2 s^3 , whereby 90 during a large portion of each revolution of the thrust-bearing U the slide-rod S is held, in opposition to the pressure of the spring S^2 , in the position to keep the loose driving-disk Q' pressed against the disk Q to rotate the 95 shaft B , and so that whenever in the step-by-step rotation of the bearing U its ledge s passes the corresponding part s' of the follower U' the rod S and shipper R will be instantly moved by the spring S^2 , so as to release the disk Q' from the disk Q and apply the brake R' to the latter disk, and thereby stop the machine. When the machine thus 100 automatically stops in using it, the sewing on of a button is usually completed, and the 105 sewed-on button should be removed from the button-holder and another button inserted in the holder, and thereby depressed and held in proper place on the fabric. By then pulling down the long arm of the lever T , which 110 may be connected with a foot-lever for that purpose, the slide-rod S will be moved so as to start the machine, as above described, and upon then holding down that lever until the 115 button-carrier shall have moved a few steps the thrust-bearing U will have turned so as to bring its surface s^2 opposite to the surface s^3 of the follower, at which time the lever T should be released to let the follower bear against the thrust-bearing until in its 120 rotation its ledge s just passes the ledge s' of the follower and the machine then stops.

The ratchet U^2 , Fig. 5, has a sufficient number of teeth to permit the mechanism to sew on a four-eyed button by stitches from eye to eye in a circuit repeatedly while the ratchet and the thrust-bearing U revolve once.

To make the mechanism capable of moving the button-holder different numbers of

steps during a rotation of said thrust-bearing, as is generally desirable and important in using the mechanism to sew on buttons through different numbers of eyes, I joint 5 the pawl-operating rod W to the arm O³ of the rock-shaft O by a pivot-coupling X, Figs. 5 and 5^a, which is adjustable along that arm to different distances from the rock-shaft, whereby the pawl V can be caused to revolve 10 the ratchet U² and thrust-bearing U by steps each equal in angular extent or degree to that of either one, two, or more teeth of the ratchet at each to-and-fro movement of said rock-shaft.

15 S⁴ is a collar adjustably secured to the rod S to variously limit the movements of that rod in the direction of the arrow v². The pawl-carrier V' is mounted loosely on the rod S, and between that pawl-carrier and the 20 bracket u' is a loose sleeve V² on said rod. The thrust-bearing U and ratchet U² are united by a sleeve u³, which is loose on the rod S and is furnished with an adjustable friction-bearing V³ to insure more accurate step-by-step movements of the ratchet by its driving-pawl.

I claim as my invention—

1. In a button-sewing machine, the combination, with a primary slide having an attached button-holder, an eccentric engaging directly with and thereby moving said slide, and means for rotating said eccentric step by step, of a secondary slide having a straight guideway for said primary slide, and thereby engaged with and operated by the primary slide, and guides to secure the movement of said secondary slide bodily and equally in every part to and fro laterally to its said guideway for the primary slide, whereby the 35 rotation of said eccentric causes the rotation of every point in said primary slide and button-holder in a circle equal in diameter to the throw of said eccentric, substantially as set forth.

45 2. In a button-sewing machine, the combination, with a primary slide having an attached button-holder, an eccentric adjustable to different distances from its axis of rotation and engaging directly with and thereby 50 operating said primary slide, and means for rotating said eccentric step by step, of a secondary slide having a straight guideway for said primary slide, and thereby engaged with and operated by the primary slide, and guides to secure the movement of said secondary slide bodily and equally in every part to and fro laterally to its said guideway for the primary slide, substantially as set forth.

55 3. In a button-sewing machine, the combination, with the primary slide having in it a socket for an eccentric, a work-holder attached to said slide, an eccentric fitting in said socket, and means for rotating the eccentric step by step, of the secondary slide having the guides for said primary slide and formed with wings transverse to said guides, and the stationary base-plate having the

guides for said wings and supporting said primary and secondary slides, substantially as set forth.

4. In a button-sewing machine, the combination, with the primary slide having in it a socket for an eccentric, a work-holder attached to said slide, and an eccentric fitting in said socket, of the secondary slide having 75 guides for said primary slide and formed with wings transverse to said guides, the stationary base-plate having guides for said wings and supporting said slides, a revolute carrier for said eccentric and supported by said base-plate, a clamp by which the eccentric is secured to said carrier, and is adjustable thereon to different distances from its axis of rotation, and means for rotating said carrier step by step, substantially as set forth. 85

5. In a button-sewing machine, the combination, with its button-holder carrier having a circular socket, of an eccentric fitting in said socket and having the perforation f², the revolute eccentric-carrier F, said eccentric and its carrier being formed with a guide-groove f in one and a corresponding tongue f' on the other, and a clamping-bolt I, extending through said perforation in the eccentric and serving to clamp the eccentric to its said 95 carrier at different distances from its axis of rotation, substantially as described.

6. In a button-sewing machine, the combination, with its button-holder carrier having a circular socket b, of the eccentric fitting in 100 said socket and having the perforation f² and projecting pin i, the revolute eccentric-carrier F, said eccentric and its carrier being formed with a guide-groove f in one and tongue f' on the other, the cap-piece I', having the perforation g and cam-slot h, and a clamping-bolt I, substantially as described. 105

7. In a button-sewing machine, the combination, with its button-holder carrier having a circular socket b, of the eccentric having 110 the perforation f² and fitting in said socket, the revolute eccentric-carrier F, having the recess j, said eccentric and its carrier being formed with guide-groove f in one and tongue f' on the other, the clamping-bolt I, stationary plate II, having the slot j', and the bolt J, fitting in said slot and movable therein into and out of said recess j, substantially as described. 115

8. In a button-sewing machine, the combination, with its button-holder carrier having a socket for an eccentric, of the eccentric fitting in said socket and having the perforation f² and projecting pin i, the revolute eccentric-carrier F, having the recess j, said 120 eccentric and its carrier being formed with the groove f in one and the tongue f' on the other, the cap-piece I', having the perforation g and cam-slot h, the clamping-bolt I, plate H, having the slot j', and the bolt J, fitting in 125 said slot and movable therein into and out of said recess j, substantially as described.

9. In a button-sewing machine, a button-holder embracing a fabric-presser having its

foot portion formed with the recess e' and furnished with lateral button-bearings k and lips l , the button-presser L , having the recess e^2 in its foot, and an adjusting clamp by which 5 said button-presser is secured to said fabric-presser and is adjustable thereon to bear properly upon buttons of very different thicknesses, substantially as set forth.

10. In a button-sewing machine, a button-holder embracing a fabric-presser having a foot-plate formed with the recess e' and furnished with the sub-feet m , having the button-bearings k and lips l , the button-presser L , attached to said fabric-presser, and adjusting- 15 clamps by which said sub-feet are secured to said foot-plate of the fabric-presser and are adjustable thereon to receive and center buttons of very different diameters, substantially as set forth.

10. In a button-sewing machine, a button-holder embracing a fabric-presser K , having a foot-plate formed with the recess e' and furnished with the sub-feet m , having the button-bearings k and lips l , adjusting-clamps by 25 which said sub-feet are secured to said foot-plate and are adjustable thereon to receive and center buttons of very different diameters, the button-presser L , having the recess e^2 , and an adjusting-clamp by which said button-presser is secured to said fabric-presser and is adjustable thereon to bear properly upon buttons of very different thicknesses, substantially as set forth.

12. In a button-sewing machine, the combination, with its button-holder carrier having a socket for an eccentric, the rock-shaft O , and means to operate it in harmony with the movements of the needle-bar, of an eccentric fitting in said socket and furnished with a 35 revolute carrier having the bevel-gear F' , and the bevel-gear M , having the ratchet M' , furnished with a pawl and pawl-carrier connected with and operated by said rock-shaft, substantially as described.

13. In a button-sewing machine, the combination, with its button-holder carrier having a socket for an eccentric, the rock-shaft O , and means to operate it in harmony with the movements of the needle-bar, of an eccentric fitting in said socket and furnished with a 40 revolute carrier having the bevel-gear F' , the bevel-gear M , having the ratchet M' , and teeth multiple of the teeth in the gear F' , pawl N , pawl-carrier N' , arm O^2 on said rock-shaft, rod N^3 , jointed at one end to said pawl-carrier, and a coupling jointed to the other 45 end of said rod and secured to said arm and adjustable thereon at different distances from said rock-shaft, substantially as described.

14. In a sewing-machine, the combination, with its work-holder, rotary driving-shaft furnished with a loose driving-disk and a fast one, means for imparting step-by-step movements to the work-holder from said driving-shaft, a shipper for said loose disk, and a slide-rod connected with said shipper, of the 50 rotary ledge-shaped thrust-bearing, means to

turn it in harmony with the step-by-step movements of the work-holder, and the follower on said slide-rod and resting against 70 said rotary bearing, and thereby keeping said loose disk pressed against the fast one during the main portion of the revolution of said thrust-bearing and instantly releasing said loose disk when the ledge in said rotary bearing passes said follower, substantially as set forth.

15. In a sewing-machine, the combination, with its work-holder, rotary driving-shaft having a disk fast thereon, means for imparting step-by-step movements to the work-holder, a brake for said fast disk, a slide-rod connected to said brake, and a spring pressing 80 said slide-rod and brake in the direction to press the brake against said disk, of the rotary ledge-shaped thrust-bearing, means to turn it in harmony with the step-by-step movements of the work-holder, and a follower on 85 said slide-rod and pressing against said rotary bearing by the action of said spring, and 90 thereby keeping the brake away from said disk during the main portion of the revolution of said bearing and permitting the brake to be instantly pressed against said disk by the action of said spring when the ledge in 95 said rotary bearing passes said follower, substantially as set forth.

16. In a sewing-machine, the combination, with its work-holder, rotary driving-shaft furnished with a loose driving-disk and a fast 100 one, means for imparting step-by-step movements to the work-holder, a shipper for said loose disk, a brake for said fast disk and secured to said shipper, a slide-rod connected with said combined shipper and brake, and a 105 spring pressing said rod, shipper, and brake in the direction to press the brake against said fast disk and to release said loose disk, of the rotary ledge-shaped bearing, means to turn it step by step in harmony with the movements of the work-holder, and the follower on 110 said slide-rod and pressing against said rotary ledge-shaped bearing by the action of said spring, substantially as set forth.

17. In a sewing-machine, the combination, 115 with its work-holder, rotary driving-shaft furnished with a loose driving-disk and a fast one, means for imparting step-by-step movements to the work-holder, a shipper for said loose disk, and a slide-rod connected with 120 said shipper, of a lever connected with said slide-rod and by which that rod and the shipper can be moved to press said loose disk against the fast one, the rotary ledge-shaped bearing, means to turn it step by step in harmony with the movements of the work-holder, and the follower on 125 said slide-rod and resting against said rotary ledge-shaped bearing, substantially as set forth.

18. In a sewing-machine, the combination, 130 with its work-holder, rotary driving-shaft furnished with a loose driving-disk and a fast one, means for imparting step-by-step movements to the work-holder, a shipper for said

loose disk, a brake for said fast disk and secured to said shipper, and a slide-rod connected with said combined shipper and brake, of a spring pressing said slide rod, shipper, 5 and brake in the direction to press the brake against said fast disk and to release said loose disk, the lever connected with said slide-rod, and by which said rod, shipper, and brake can be moved in the opposite direction, the rotary ledge-shaped bearing, means to turn it step-by-step in harmony with the movements of the work-holder, and the follower on said slide-rod and pressing against said rotary ledge-shaped bearing by the action of said 5 spring, substantially as set forth.

19. In a button-sewing machine, the combination, with its button-holder carrier, rotary driving-shaft furnished with fast and loose driving-disks, and a combined shipper 5 and brake therefor, the rock-shaft O, means to operate it from said driving-shaft, and means to impart step-by-step movements to the button-holder carrier from said rock-shaft, of the slide-rod S, connected with said combined shipper and brake, a spring to press and move said slide-rod endwise, the ledge-shaped revoluble thrust-bearing U, its follower U', and the ratchet U² on said thrust-bearing and furnished with a pawl and pawl-carrier 50 connected with and operated by said rock-shaft, substantially as described.

20. In a button-sewing machine, the combination, with its button-holder carrier, rotary driving-shaft furnished with fast and loose driving-disks and a combined shipper 5 and brake therefor, the rock-shaft O, means to operate it from said driving-shaft, and means to impart step-by-step movements to

the button-holder carrier from said rock-shaft, of the slide-rod S, connected with said combined shipper and brake, a spring to press and move the slide-rod endwise in one direction, the lever T, connected with said slide-rod, and by which the slide-rod can be pressed and moved endwise in the opposite 45 direction, the ledge-shaped revoluble thrust-bearing U, its follower U' on said slide-rod, and the ratchet U² on said thrust-bearing and furnished with a pawl and pawl-carrier connected with and operated by said rock-shaft, 50 substantially as set forth.

21. In a button-sewing machine, the combination, with its button-holder carrier, rotary driving-shaft furnished with fast and loose driving-disks and a combined shipper 55 and brake therefor, rock-shaft O, means to operate it from said driving-shaft, and means to impart step-by-step movements to the button-holder carrier from said rock-shaft, of the slide-rod S, connected with said combined shipper and brake, spring S², revoluble ledge-shaped thrust-bearing U, its follower U', ratchet U² on said thrust-bearing and furnished with a pawl and pawl-carrier V', arm 60 O³ on said rock-shaft, rod W, jointed at one 65 end to said pawl-carrier, and a coupling jointed to the other end of that rod and secured to and adjustable along said arm, substantially as set forth.

In testimony whereof I hereunto set my 70 hand, in the presence of two subscribing witnesses, this 19th day of August, 1889.

JOSEPH P. HALLENBECK.

Witnesses:

JNO. P. CARR,
JAMES T. HOGAN.
